UNITED STATES PATENT OFFICE.

HENRY L. BROWN, OF NEW YORK, N. Y., ASSIGNOR TO BROWN SPIN-WRIGHT COMPANY, OF NEW YORK, N. Y., A CORPORATION OF NEW YORK.

SPINDLE.

1,149,719.

Specification of Letters Patent.

Patented Aug. 10, 1915.

Original application filed January 6, 1910, Serial No. 536,681. Divided and this application filed November 30, 1910. Serial No. 594,960.

To all whom it may concern:

Be it known that I, HENRY L. BROWN, of New York, N. Y., have invented certain Improvements in Spindles, of which the following description, in connection with the accompanying drawings, is a specification, like numbers on the drawings designating like parts.

This invention relates to apparatus of the nature of spinning frames, and is of particular utility when embodied in mechanism for treatment of cotton, wool, flax, ramie, silk, artificial silk, silk waste, and like fibers, fibrous materials and filaments as, for example, mechanism for spinning, twisting, winding, quilling and analogous operations, although I contemplate the use of my improvements in any field for which they are adapted by their nature, an important object of my invention being to provide improved mechanism for driving devices such as spindles positively, using preferably an apertured metallic driving band in combination with a gear having helical teeth, in accordance with the invention forming the subject matter of my application for United States Letters Patent Serial No. 536,681, filed January 6, 1910, from which this present application has been divided.

Another important object of my invention is the provision of an improved coupling device for connection of the spindle (*i. e.* the rotating blade, shell or similar member which receives the material to be treated) with the rotatable actuating member driven by the band, and for this purpose I provide connectors preferably comprising flexible devices of a prong-like character extending between the rotatable members, and which may conveniently be mounted to form a unitary structure with one of said members, being presented thereby in position to enter the material of, or be engaged with, the other member removably, so that the members may be readily separated when desired. This coupling is of general utility for the connection of spindles and their "whirls," using that term broadly for the designation of the part of the spindle which receives the driving motion to be communicated to the spindle proper, the term "whirl" being used without any limited technical significa-

tion, and the coupling is of particular utility in connection with the helical gear to which reference has already been made.

Among other objects of notable importance provided for by my improved prong coupling device, may be mentioned the construction and arrangement of the same in such a manner as to promote the "flexibility" of the spindle as a whole, permitting the blade to locate itself for rotation about an axis other than the normal, and also to accommodate certain nutative and gyratory aberrations of the spindle under the influence of such adventitious disturbing factors as blows or knocks by the operator, asymmetrical winding on of the load, or the tremors which frequently run over a frame on the occasion of a disturbance at any part thereof; also, to obviate one fruitful source of such disturbances by permitting a limited play of the whirl or gear along the axis of the spindle, without interfering with co-rotation of the whirl and spindle blade in coupled relation; and still further to provide for the initiation of the co-rotative action, by a frictional engagement between portions of the spindle blade and whirl automatically when the blade is introduced to the bolster, eventuating in positive engagement as the speed of the blade approaches that of the whirl, this provision permitting continuous rotation of the whirl, if desired, in the absence of the blade, it being usually more convenient to permit the whirl to continue its rotation, independently of the spindle blade, when actuated positively by a band of my improved type, at speeds approximating 10,000 turns a minute.

When provision is made for such frictional initiation of the co-rotative engagement of the blade and whirl, I prefer to provide one of these members with a wear plate of suitable material such as hardened metal, which may conveniently be stamped or cut out in the form of an annulus, and may be provided with apertures or recesses to be entered by the prongs constituting my preferred form of coupling device, the latter being preferably of resilient material to give slightly under the torque arising at the initial engagement of a blade at rest with a whirl rotating at high speed.

An object of very notable importance is

the construction and arrangement of the bearings between the gear or whirl of my improved type, and the bolster, (using that term broadly to designate the spindle member which supports the blade and whirl for co-rotation,) so that my improvements may be embodied readily in existing spindle structures without necessitating the abandonment of the many millions of spindles now in use, a very large proportion of which existing spindles comprise tubular bolsters; and in accordance with this object of my invention I have provided a type of gear to receive which such bolsters may be adapted by simply reducing the exterior of the bolster to a cylindrical surface serving as the axial bearing for the gear, and I prefer to form this surface of the bolster, and the axial bore of the gear, of such relative dimensions as to leave room for a sleeve or bushing member surrounding the neck of the bolster, between it and the gear. This enables me to adopt a gear of standard exterior and interior diameter, regardless of the diameter of the bolster, using a filling bushing of suitable thickness therebetween, with an easy slip fit. Such a bushing may be used advantageously to afford a compound bearing, if left free to rotate relatively to the bolster and the gear or whirl, distributing the friction, and in accordance with another important object of my invention this bushing may form part of a stop-motion, the provision of which may be desired in certain operations, to permit disconnection of the spindle from the gear before the spindle is grasped for its removal from the bolster, or if for any reason it is desired that the spindle should be left at rest in the bolster while the gear continues to rotate. The preferred form of such a stop-motion, utilizing a bushing of the type thus described, comprises a device which may be engaged with the bushing to move it axially between the gear and bolster into a position of engagement with the spindle blade, for normal co-rotation of the spindle and gear, to which gear the bushing may be connected by suitable means, as by prongs mounted on one of the members, as for example the bushing, and arranged to enter recesses in the other member, as for example the gear, so that normally the bushing rotates with the gear, and is connected at times with the spindle blade, one suitable form of such connection comprising a cup-like device forming a unitary structure with the bushing and arranged to present upwardly a cavity to be entered by a collar, or other suitable portion of the spindle blade, of suitable contour. Such contour may be provided for conveniently by slabbing off the periphery of the spindle or its collar at a plurality of regions, say three, and forming the interior of the bushing cup for en-

gagement with the substantially triangular shoulder thus formed. The cup may be formed for this purpose with a solid rim surrounding a cavity corresponding exactly with the spindle collar, or may have a circular rim provided with springs located at chords corresponding to the flat portions of the spindle collar. The latter construction may be adopted as a convenient means to permit the operator to grasp the spindle, or the bobbin thereon, while the same is rotating at top speed, in which event the bushing and its cup will continue to rotate, the resiliency of the springs permitting the cup to turn around the spindle collar. Ordinarily, however, I prefer to utilize for the disconnection of the spindle blade from the gear the same means which is employed to cause co-rotative engagement of the cup with the spindle collar, or rather to position the bushing for such co-rotative engagement, and for this purpose I may provide an arm extending from an actuator preferably taking the form of a vertical rod which, when it is raised, causes the arm to engage the bushing and lift it with its cup into position for engagement with the collar on the spindle blade, and when the rod is dropped, this arm is withdrawn and permits the bushing to drop, with its cup, away from the spindle collar.

The connection between the arm and the bushing will preferably be such as to leave the bushing free to turn with the gear and, if desired, provision may be made to enable the arm to move the bushing positively out of, as well as into, position for engagement with the spindle blade. The rod for operating the stop may be actuated by means of any suitable device, and I prefer to provide means suitable to enable the operator to disconnect the spindle and gear readily, such means preferably taking the form of a spring mounted on the rail-supporting structure, and operable by the knee of the operator, so that the hands will be left free for manipulation of the bobbin.

In accordance with another object of notable importance, I provide means for the automatic operation of the spring, and for the consequent release of the operating rod and disconnection of the spindle blade and whirl, upon failure of the thread between the rolls and spindle, this being accomplished preferably by a magnet acting on the spring and working in an electrical circuit constructed and arranged to be closed by a detector which is operated by failure of the thread or passage of a knot or uneven portion thereof.

The return of the bushing and cup for engagement with, and operation of, the spindle blade, may conveniently be accomplished by pulling upward the operating rod, a suitable handle being preferably provided for

that purpose, and the spring and rod being so constructed that the spring will automatically catch in a notch on the rod when the bushing cup is in position to be engaged 5 with the spindle collar, and as the spindle is movable co-axially with respect to the bushing, the latter may be raised to a suitable position before the spindle blade is dropped into place, and the rotation of the 10 blade will be initiated by frictional engagement between those portions of the bolster cup and spindle collar which do not match, until the speed of the spindle blade approximates that of the bushing cup, when the 15 weight of the spindle will cause it to drop, and seat itself, the foot of the spindle resting on the usual step preferably, provided near the bottom of the bolster, which supports the weight of the spindle, so that there 20 is no strain on the gear. The latter is connected to the spindle blade by the cup, through the medium of the prongs extending therebetween, the latter being preferably slightly resilient, and the various connections 25 being made easy to permit "flexibility" of the spindle. In order to augment the initial frictional engagement between the spindle blade and cup, the spindle collar may have a downwardly projecting extension, preferably tapered slightly, to enter a 30 corresponding surface in the bore of the cup or bushing, the contact between this tapered extension and its seat operating to bring up the speed of the spindle blade gradually but 35 quickly to the point where the blade will seat itself for positive co-rotation with the cup, bushing and gear under the action of the band.

The various features of my invention will 40 be illustrated and described fully in the accompanying drawings and specification, and pointed out in the claims.

In the drawings, Figure 1 is a view in side elevation of a spinning spindle, shown in 45 place upon a rail, and in the construction of which my improvements have been embodied; Fig. 2 is a similar view, in front elevation with the parts only partly assembled, the rail and part of the bolster being broken 50 away; Fig. 3 is a view, similar to Fig. 1, of a modified form of spindle; Fig. 4 shows the parts of the spindle illustrated in Fig. 3, partly assembled; Fig. 5 is a fragmentary 55 detail view showing in plan the spindle collar separately; Fig. 6 is a plan view of the bushing, shown separately; and Fig. 7 is a view similar to Fig. 6 of a modified form of bushing cup; while Fig. 8 is a view in front elevation of another modification of spindle, and gear, part of the latter being broken 60 away to show interior construction.

In the embodiment of my invention selected for illustration and description to enable ready and complete understanding of 65 my improvements, the part designated by

the reference numeral 1 is a spindle whirl, which may be of any suitable material and construction, the preferred form thereof herein illustrated being shown as a gear having an annular hub provided with helical 70 teeth 2 of which there may be any suitable number, having the pitch and lead which may be found appropriate to the exigencies of the particular installation. In accordance with one feature of my invention, this 75 gear or whirl is preferably driven by a suitable band 3 having apertures with inclined walls 4 to receive the teeth 2, the latter being engaged with the walls 4, which act upon lengthwise movement of the band 3 to ro- 80 tate the gear.

The gear or whirl 1 may be connected in any suitable manner with the rotatable spindle member which is to receive the material to be treated, as for example the blade 5 85 having a portion 6 to enter a suitable bolster 7, and as one convenient form of construction to couple the gear or whirl 1 therewith I have shown coupling devices 8 which in the instance illustrated comprise a plurality of prongs extending between the whirl 1 and a collar 9 with which the spindle blade is provided, and which may be of any suitable material and construction. The collar 9 is shown, by way of example, 90 as a separately formed disk driven upon the portion 6 of the spindle blade until it reaches the larger bobbin-receiving portion 5, the latter forming a shoulder at the region 10, against which the part 9 may be seated. 100

In accordance with my invention the prongs 8 may be of considerable extent, preferably of slightly resilient material, such as steel wire, and secured to one of the members of the spindle forming a unitary structure therewith and being presented in position for engagement with the other rotatable member, this being accomplished by driving the prongs 8 into sockets in the upper surface of the whirl 1, whence they project upward into position to enter holes 11 in the part 9, as illustrated in Fig. 1, which shows the parts of the spindle in operative position. The number of these prongs and their spacing may be varied as desired, and they 110 may be placed at regular or irregular distances apart. In Fig. 8 I have shown three prongs at irregular distances. In Fig. 3, I have indicated three prongs at regular distances, 120 degrees apart. 115

In accordance with a valuable feature of my invention, I prefer to construct the whirl or gear 1 so that it can be used as a standard driving member for a wide variety of spindles, utilizing the bolster of tubular shape which is common to much the larger portion of spindles in use throughout the world and of which the inner construction may vary considerably without interfering 125 with the adaptation of the bolster to service 120.

as a bearing member for my improved whirl or gear. Any suitable structure of bolster may be utilized, and as one convenient form of such bolster I have shown at 7 a bolster 5 having a threaded portion 18 with flange 19 and nut 20 to permit attachment of the bolster to a suitable rail 21, the rail being shown as having an aperture 22 sufficiently large to permit adjustment of the threaded 10 stud 18 therein if desired, and this bolster is shown as having also an upwardly extended neck 17 preferably cylindrical in contour and preferably somewhat smaller in diameter than the tapered portion of the bolster 15 below the part 17 so that a shoulder is formed at 27.

In accordance with my invention in its preferred form the whirl or gear 1 finds its bearing upon this neck 17, and in accordance 20 with my preferred construction of the gear, the inner bore 23 of the latter is preferably made of considerable diameter so that it can be fitted readily to bolsters having necks of various diameters without necessitating alteration of the gear after it has 25 been hardened, as I prefer to construct the gear of steel and harden it before it is put into use.

Existing bolsters may readily be adapted 30 to receive the gear by turning down their peripheries to a uniform diameter as shown at 17, and if the neck is too narrow for a proper bearing fit of the gear thereupon, a bushing 24 or sleeve 24 may be interposed 35 between the bolster neck and the gear, and may be left loosely therebetween, rotatable independently of both whirl or gear and the bolster, thus constituting a compound bearing member and distributing the friction. 40 Ordinarily the length of the bearing afforded by this bushing or by the bolster neck 17 will be sufficient to permit one-eighth to a quarter of an inch play of the whirl or gear 1 along the axis of the spindle, so that if 45 there should be any slight variation in the horizontal position of the band the gear can follow the band without interfering with the co-rotative movement of the gear and spindle blade, this play being also permitted, as 50 heretofore described, by the apertures 11 in the spindle part 9, wherein the prongs 8 are free to move up and down. For this purpose the bushing 24 is shown as somewhat longer than the gear 1, as seen clearly in 55 Fig. 1.

The form of spindle above described may be used to notable advantage in situations where there is but little need for frequent removal of the spindle blade 5, but it will 60 be noticed that there is nothing to interfere with such removal on occasion, and if desired means may be provided to utilize the bushing member 24 as means to disconnect the spindle blade 5 from the gear 1 to permit ready removal of the spindle by hand 65

or to permit the spindle blade to come to rest for any purpose desired. Any suitable device may be utilized to accomplish such stoppage and by way of example of one such construction, I have shown in Fig. 1 70 a device comprising a bell crank lever 25 mounted pivotally at 26 upon a suitable support 27 which may be connected to the rail and secured in place thereupon by the nut 28, this lever having an arm 29 which takes 75 into a groove 30 in a collar 31 preferably forming part of the bushing 24, and when the lever 25 is moved toward the left, manually or by any suitable means (not shown) the arm 29 will be lifted, carrying with it 80 the collar 31 and bushing 24 until the upper end of the bushing is engaged with the part 9 on the spindle blade and lifts the spindle blade until the part 9 is clear of the prongs 8, after which the spindle blade 5 may be 85 grasped with impunity by the operator, either before or after it comes to rest, the whirl or gear 1 and bushing 24 being free to rotate with the band 3 as before, such rotation of the bushing being permitted by 90 the location of the arm 29 in the groove 30.

As long as the bushing is held in its upward position, the spindle will be prevented 95 from co-rotative engagement with the prongs 8, but as soon as the lever 25 is released the weight of the spindle blade 5 and its related parts, such as the bobbin (not shown) will press the bushing 24 downward and the prongs 8 may enter the holes 11, the foot 32 of the spindle will seat itself on the step 33 (see Fig. 1) and the spindle blade 5 will be driven by the band 3 through the medium of the whirl or gear 1, prongs 8 and spindle part 9.

The reference numeral 34 designates a 105 detent to hold the lever 25 in adjusted position.

The connection between the spindle blade and whirl or gear may be varied to meet the exigencies of particular installations, and I have shown in Figs. 3 and 4 a modified form of such a connection, differing from the connection just described somewhat in details of construction, and principally in that the normal position assumed by the coupling parts under the influence of gravity, is one of disconnection of the spindle blade from the whirl or gear, so that a simple touch of the mechanism is sufficient 110 to effect the stoppage of the spindle blade. This result may be secured by any suitable construction embodying my invention, and by way of example of such construction I have shown a bushing 240 interposed between a gear 100 and the neck 170 of a bolster 70 substantially in the manner described with reference to the bushing 24, gear 1 and neck 17 of the bolster 7 already described and shown in Figs. 1 and 2, the bushing 240 being however connected, preferably, for 120 125 130

constant rotation with the gear 100 by prongs 80 entering holes 110 in the material of the gear, the holes and prongs being of suitable length to permit a considerable play of the bushing along the axis of the spindle without interfering with co-rotation of the bushing and gear under the action of the band 300 whose aperture walls 400 are engaged actuatingly with the helical teeth 200 of the gear, the band being moved longitudinally in a manner common to endless driving bands by a suitable source of power not shown.

I have shown the prongs 80 as mounted in a cup-like member 81 formed integrally, or as a unitary structure with the bushing 240, the cavity 82 of the cup being of a contour suitable to receive, and be engaged actuatingly with, a suitable part of the spindle blade 50, such a part being provided for by the collar 90 best seen in Fig. 4, the collar being driven upon the portion 60 of the spindle blade until it reaches a shoulder 101 formed by the larger portion 50 of the spindle blade which is to receive the bobbin in the usual manner.

Any convenient contour may be adopted for the above purpose, and that selected for illustration, by way of example, is best seen in Figs. 5 and 6, the collar 90 being of generally circular periphery slabbed off at suitable regions as shown at 91 to form flats, of which there are three in number in the instance illustrated, while the cavity 82 of the cup 81 has a similarly triangular shape, with flats 83 to be engaged with the similar flats 91 upon the collar 90 when the latter enters the cavity 82.

Normally, when the spinning frame containing the spindles is in operation, the parts are as shown in Fig. 3, the bushing 240 being supported with its cup 81 engaged with the collar 90, and with its prongs 80 engaged with the gear 100, the latter being driven by the band 300 to actuate the spindle blade 50, and to maintain this position of the parts, any suitable structure may be provided.

For the sake of permitting ready disconnection of the parts, I have shown as one convenient device for holding the operating parts in connected relation an arm 290 secured by a set screw 291 in adjusted position upon an operating rod 250, the latter being mounted for a vertical movement in a bracket 270 secured by a bolt 280 to a part 211 of the rail structure 210, and the arm 290 is shown as having a portion 291 embracing the stud 170 and engaged with the bushing 240 at 241 near the lower end of the bushing, so that the bushing can be moved up and down by the arm 290, when the latter is operated by the rod 250, suitable means such as the handle 251 being preferably provided to permit manual operation

of the rod, and means being provided also preferably to hold the rod positively in its upper position, with the operating parts in operative connection, as illustrated in Fig. 1.

Any suitable form of holder for this purpose may be utilized, and as one convenient holding device I have illustrated a spring 252 having a portion 253 extending into position to be engaged with the rod 250 which may conveniently have a notch 254 at that portion of the rod where the spring portion 253 is located, and I prefer to have the spring 252 of sufficient extent to carry it down along the rail portion 211 to a region about opposite the knee of the operator, where it may be secured by suitable fastening means such as the screw 255, so that a simple, quick pressure of the knee against the spring 252 will push the spring part 253 inward, clearing it from the notch 254, and the rod 250 and arm 290, thus released, will permit the bushing 240 and its cup 81 to fall of their own weight. Should it be desired to operate the bushing positively the handle 251 may readily be grasped and thrust downward, but ordinarily the operation of the spring 252 by the knee of the operator will suffice, leaving the operator's hands free for manipulation of the bobbin.

Instead of the manual operation of the stop-motion, or in addition thereto, suitable means may be provided to operate the same automatically, and as one convenient form of device for effecting this, I have shown an electrical magnet 256 bolted at 257 to the rail member 211, and connected by suitable conductors 258 to any suitable form of detector (not shown) normally in engagement with the thread passing from the usual thread guide, a breakage of the thread permitting the detector to drop, completing a circuit which operates the magnet 256, the latter drawing the spring 252 toward it and withdrawing the spring part 253 from the notch 254, releasing the rod 250, arm 290, bushing 240 and cup 81, so that the latter drops away from the collar 90 and the spindle blade 50 is allowed to come to rest.

To start the spindle blade again, after the thread has been pieced up and the detector replaced in position to break the circuit, the handle 251 is grasped and raised until the spring part 253 is engaged with the notch 254 thus lifting the arm 290 and bushing 240 until the upper surface of the cup 81 contacts with the lower surface of the collar 90, it being understood that the cup 81 is being rotated rapidly under the influence of the prongs 80 and gear 100 driven by the band 300.

The collar 90 will not enter the cavity 82 of the cup at once, and the spindle blade 50, is raised slightly within the bolster 170, its

collar 90 resting on the cup 81, but the friction of the collar and cup gradually but quickly brings the spindle blade to approximately the same speed as the cup, and then the weight of the spindle blade causes the spindle to seat itself with its collar in the cup and the flats 83 of the cup in driving engagement with the flats 91 of the collar. This initial frictional engagement is augmented preferably by providing a tapered extension 92 below the collar 90, and by providing the cup with a tapered seat 84 to receive the extension 92, the loose entrance of the spindle blade prior to its seating inducing preliminary frictional engagement between the surfaces 92, 84 in addition to the frictional engagement between the bottom of the collar 90 and the solid rim portions of the cup adjacent to the flats 83, so that the spindle blade quickly picks up speed and is seated in a few seconds, after which the spindle is actuated positively and continuously by the band 300.

In Fig. 7 I have shown a modified form of connection in which a bushing 241 has a cup 181 the rim of which is circular, and which is provided with springs 183 extended along chords of the circular periphery corresponding to the flats 91 upon the collar 90 of the spindle blade 50 shown in Fig. 4, these springs 183 taking the place, and fulfilling the functions, of the flats 83 upon the cup 81 shown in Fig. 6, with this difference of operation, that when the springs 183 are used, the spindle blade 50 may be grasped and held manually and withdrawn if desired, the springs 183 giving, so that the cup 181 continues to rotate under the action of prongs 180 similar to the prongs 80 shown in Fig. 3 as actuated by the gear 100, the bushing 241 being capable of substitution in every respect for the bushing 240, except for the yielding action of the springs 183, the latter being sufficiently stiff to insure positive actuation of the spindle blade 50 by their engagement with the flats 91 on the collar 90.

In Fig. 8 I have illustrated a modified form of coupling device in which prongs 88 of steel wire about an inch long are fixed in a collar 99 upon a spindle 55 seated in a bolster 77, the prongs being presented downward for engagement with a gear or whirl 111 having helical teeth to be operated by an apertured driving band of the type shown in Figs. 1 and 3, and the gear finding its bearing on the neck 177 of the bolster, which extends up into the axial bore 230 of the gear, the latter having recesses 402 to receive the prongs 88, being deep enough to permit some axial play of the gear 111 relatively to the spindle blade 55.

I prefer to provide the gear 111 with wear-plates 316 secured to the gear by suitable fastening means, such as the screws 317,

and the wear-plates will preferably have recesses or apertures 404 to receive the couple prongs 88. These annular wear-plates may be punched out of hardened steel plates and serve to resist the friction of the ends of the prongs 88 during the initial period of frictional engagement after the spindle blade 55 is dropped into the bolster 77, and until the acceleration of the spindle blade permits the prongs to enter the openings 402, and the spindle blade 55 to seat itself in the bolster 77 for positive co-rotation with the gear 111. In order that this engagement may not occur with excessive torque, I may space the prongs 88 at irregular distances, as indicated, delaying the positive engagement.

The face-plates 316 may serve the additional purpose of retaining members to hold in place the annuli 223 upon which the teeth 222 are preferably formed, as in the instance illustrated in Fig. 8, and if desired other fastening means may be furnished for these annuli, such as the peripheral screws 224.

The reference numeral 302 indicates a bobbin, which may have notches 303 to receive lugs 199 on the collar 99, thus insuring positive rotation of the bobbin with the spindle 55, gear 111 and band.

Having illustrated and described my invention thus fully and suitable means by which the same may be carried into effect, I wish it to be understood that I do not limit myself to the specific structural forms and materials selected for illustration and description, nor in general otherwise than as set forth in the claims read in connection with this specification, and attention is further called to the fact that certain portions of the subject matter illustrated herein by way of example is not claimed specifically herein, for the reason that it forms the subject of claims in my above-mentioned co-pending application Serial No. 536,681, and of my co-pending application Serial No. 675,403, filed February 5, 1912, the latter application and my present application having been divided from my aforesaid application Ser. No. 536,681.

What I claim as new, and desire to secure by Letters Patent of the United States is:—

1. A spindle-support and actuating mechanism; comprising a bolster having means to receive a spindle and support the same rotatably; and a rotatable member mounted on said bolster and rotatable co-axially with respect to said spindle but independently thereof; said member being movable along the axis of said bolster and spindle during said rotation; substantially as described.

2. A spindle-support and actuating mechanism; comprising a bolster having means to receive a spindle and support the same rotatably; and a rotatable member mounted on said bolster and rotatable co-axially with

respect to said spindle but independently thereof; and means to connect said rotatable member and spindle at times to actuate said spindle, said means permitting movement of 5 said rotatable member along the axis of said spindle during co-rotation of the two, with said spindle upon its step.

3. A bolster for a spindle, said bolster having a neck to receive rotatably a member 10 arranged co-axially with respect to said spindle; a member rotatable and movable axially upon said bolster independently thereof, and means to connect said member at times with said spindle to permit actuation 15 thereof by said member; substantially as described.

4. A bolster, having a neck; a rotatable actuating member upon said neck; and a spindle member within said neck and movable 20 co-axially into actuating relation with said actuating member, said actuating member being capable of co-axial movements relatively to said spindle when in actuating connection therewith.

5. In a spindle; a plurality of co-axially arranged rotatable members, one of said members having a plurality of prongs, and another of said members having a part recessed at intervals to be engaged with said 30 prongs, said prongs being of sufficient resiliency to yield slightly at the moment of engagement of said members for positive co-rotation when one has been rotating at a higher speed than the other prior to such 35 positive engagement.

6. In a spindle; a plurality of co-axially arranged rotatable members, one of said members having a plurality of unevenly spaced prongs, and another of said members 40 having a face part of wear-resisting material recessed at intervals corresponding with said prongs and to be engaged therewith frictionally, at times and positively at times, said prongs to enter said recesses for positive 45 engagement with the walls thereof, and of sufficient length to permit some co-axial play of said members, each without disturbing the other, or causing uncoupling.

7. In a spindle; a plurality of rotatable 50 members, including a spindle-blade, and one of said members having a part constructed and arranged to be engaged co-actuatively with said other member by frictional contact until acceleration of the speed of the 55 driven member to approximately the speed of the driving member, said members having means to be engaged positively for co-rotation of said members at the same speed, and means to permit movements of one of said 60 members relatively to said spindle blade along the axis thereof during co-rotation of said members.

8. In a spindle; coupling means comprising a member with unevenly spaced prongs; 65 and a member with correspondingly spaced

recesses to receive said prongs at times to permit positive actuation of one of said members by said other member; said members being constructed and arranged for frictional engagement with each other at 70 times preparatory to said positive engagement; substantially as described.

9. A compound spindle-driving whirl having a part to be engaged frictionally with a spindle member at times to initiate 75 rotation of said spindle; and a part having a recess to receive a prong carried by said spindle to permit said spindle and whirl to be coupled for co-rotation, while permitting axial movements of said parts relatively to 80 each other, during rotation of said spindle in fixed position on its bearing; substantially as described.

10. Coupling means for spindles of the class described; having a rotatable blade 85 member and an independently rotatable whirl member arranged co-axially with respect to said blade; said coupling means comprising a resilient prong on one of said members to be engaged with a surface upon 90 said other member frictionally during the initiation of rotation of said blade by said whirl, and means to be engaged positively with said prong upon acceleration of the speed of said blade, to permit the co-rotation 95 of said blade by said whirl at the same speed therewith; substantially as described.

11. A spindle having a prong to be engaged with an actuating whirl for rotation thereby, permitting axial movements of said 100 whirl on said spindle; substantially in the manner and for the purpose set forth.

12. A spindle having a plurality of resilient driving prongs to be engaged with a driving whirl frictionally at times and 105 positively at times.

13. A spindle having a plurality of driving prongs spaced unevenly; substantially in the manner and for the purpose set forth.

14. As an article of manufacture; a face-plate for spindle-whirls of the class having a rotatable hub with facial recesses to receive a pronged co-acting member; said face-plate being formed of wear-resisting material to be engaged frictionally with said prongs for 110 initiation of co-rotation, and having openings to register with said facial recesses and give access thereto for said prongs; substantially as described.

15. A spindle; comprising a rotatable 120 member to receive the material to be treated; a driving-band; a floating whirl; and means to connect said whirl positively with said band and rotatable member respectively to permit actuation of said rotatable member 125 by said band.

16. A spindle; comprising a rotatable member to receive the material to be treated; a driving-band; a whirl; means to connect said band and whirl positively; a 130

device movable along the axis of said spindle and relatively thereto having means to connect said whirl with said rotatable member to permit actuation of said rotatable member by said band; and means to permit the operator to effect the disconnection thereof.

17. A spindle; comprising a rotatable member to receive the material to be treated; a driving-band; a whirl; means to connect 10 said band and whirl positively; and a bushing movable along the axis of said spindle and relatively thereto; having means to connect said whirl with said rotatable member to permit actuation of said rotatable member by said band.

18. A spindle; comprising a rotatable member to receive the material to be treated; a whirl; a driving band; a connecting device for said whirl and rotatable 20 member, said device normally occupying a non-connective position relatively to one of said members; and means to hold said device positively in connective position.

19. A spindle; comprising a rotatable member to receive the material to be treated; 25 a whirl; a driving band; a connecting device for said whirl and rotatable member, said device normally occupying under the influence of gravity, a non-connective position relatively to one of said members; and means to sustain said device positively in connective position.

20. A spindle; comprising a rotatable member to receive the material to be treated; 30 a whirl member; a cup on one of said members; and a collar on said other member; said cup and collar fitting each other for co-rotation when engaged; and controlling devices for the engagement and disengagement of said cup and collar.

21. A spindle; comprising a rotatable member to receive the material to be treated, said member having a collar with a flat driving surface; a whirl member having a cup 45 with a coöperating flat driving surface; and means to move said cup into position to re-

ceive said collar within the cavity of said cup.

22. A spindle; comprising a bolster, a member rotatable in said bolster and to receive the material to be treated; a whirl rotatable upon said bolster; a coupling bushing interposed between said bolster and whirl; and coupling prongs extending between and connecting said bushing and whirl, said prongs being mounted on one of said members and entering sockets in said other member, said bushing being movable axially relatively to said other members, while still connected for co-rotation with 60 said whirl, into positions to connect and disconnect said whirl and rotatable material-receiving member.

23. A spindle; comprising a bolster, a member rotatable in said bolster and to receive the material to be treated; a whirl rotatable upon said bolster; a coupling bushing interposed between said bolster and whirl; and coupling prongs extending between and connecting said bushing and 65 whirl, said prongs being mounted on one of said members and entering sockets in said other member, said bushing being movable axially relatively to said other members, while still connected for co-rotation with 70 said whirl, into positions to connect and disconnect said whirl and rotatable material-receiving member; and means to move said bushing axially, said means including an 75 arm to be engaged with said bushing, a rod upon which said arm is mounted, and a spring catch to hold said rod in position, said spring being located in position to be operated by the knee of the operator, to effect change in the position of said bushing. 80

Signed at New York in the county and State of New York this 28th day of November, 1910.

HENRY L. BROWN.
